UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,271,780.

Specification of Letters Patent. Patented July 9, 1918.

Application filed October 7, 1916. Serial No. 124,250.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My invention relates to typewriting machines and more particularly to the mounting of the platens of such machines.

My invention has for its principal object to provide means for adjusting one end of the platen on its support with relation to 15 the other end of said platen so that the types coöperate with said platen alike at both ends of the carriage travel.

To the above and other ends which will hereinafter appear, my invention consists in 20 certain features of construction and combinations and arrangements of parts, all of which will be fully set forth herein and particularly pointed out in the claims.

In the accompanying drawing,

25 Figure 1 is a fragmentary left-hand side elevation partly in section of the upper part of a typewriting machine having my invention embodied therein, only those parts being shown which contribute to an understanding of the invention.

Fig. 2 is a front view of the left-hand end of the platen and its supporting means, parts being shown in section on the line $\alpha\alpha$ of Fig. 1.

35 Fig. 3 is an end elevation, partly in section, showing the left-hand end piece of the platen frame and my adjustable devices, the section being on the line yy of Fig. 2 and looking in the direction of the arrows at said 40 line.

Fig. 4 is an enlarged fragmentary section on the line zz of Fig. 3.

Fig. 5 is a diagrammatic plan view on a small scale of the platen, and illustrating, in 45 an exaggerated way, the character of the adjustment to be obtained by my novel means.

Fig. 6 is a vertical longitudinal section of the adjustable supporting means for one end 50 of the platen shaft.

I have shown my invention embodied in a machine which in some respects is similar to, and may be identical with, the No. 10 Remington typewriter, but which in other

respects is different from that machine. The 55 machine shown in the drawing comprises a top plate 1, which below the platen 2, is depressed into a trough-like form as in the No. 10 Remington. Said platen has an axle 3 which is mounted by means presently to be 60 described in a platen frame, of which only the left-hand end piece 4 is shown in the drawing. Said platen frame may be mounted with provision for an up and down case-shift motion in a carriage truck, which truck 65 is not shown in the drawing but which may be identical with that of the No. 10 Remington machine. Said Remington truck comprises a rectangular frame, the front and rear bars of which are in the nature of 70 grooved rails, which through roller bearings coöperate with stationary rails mounted on the top plate 1. All of this mechanism, including the shiftable platen frame, is familiar to those skilled in the art and I 75 have not deemed it necessary to illustrate it here, one reason being that the invention may be used in a shifting segment machine and in which there is no separate carriage truck, such a machine for example as that 80 known as the Monarch.

The type action, a part of which is shown, differs from that of the Remington No. 10 machine, however, the type bars 5 being guided in a series of radial slots 6 in a type 85 bar segment 7 and all of said type bars pivoted on a curved wire 8 suitably seated in a curved groove in the rear face of said segment. Said segment is secured in any suitable way to brackets 10 of the top plate 1. 90 Each of said type bars has a slot 11 in which plays a pin 12 projecting from a key operated sub-lever 13, the whole construction being such that when a key is depressed said pin 12 moves toward the front of the machine and throws the type bar from its normal horizontal position up to its printing position shown in Fig. 1. One or the other of the two types 14 will strike against the front face of the platen depending on the 100 case position of the platen. A center-guide 15 for the type bars is mounted on the segment 7. On the front face of said segment, as in some prior machines, there is an anvil 16 formed on a curve in a vertical plane and against which each type bar strikes at about the instant of printing. It is always desirable to have the two ends of the platen bear 105

at all times the same relation to the types when the platen is struck by said types but this is especially important when an anvil such as that shown at 16 is employed.

5 According to my invention the right-hand end of the platen may be supported by the right-hand end piece of the platen frame in the usual way, but the left-hand end of the platen is mounted in the left-hand end piece 10 4 with provision for adjustment front and back, or toward and from the point at which the type on an operated type bar is arrested by the anvil 16. For this purpose I have provided a plate 17 which is secured to the 15 inner face of the end piece 4. The axle 3 passes through a sleeve 18, part of which is exteriorly screw threaded, and the plate 17 has a hole which is correspondingly internally threaded and the sleeve 18 is screwed 20 into said plate. Said sleeve has an enlarged part 20 forming a shoulder which is screwed up tight against the plate 17, said enlarged part as here shown being formed polygonal so that a wrench can be used on it. A check 25 nut 21 is also screwed on to the threaded part of the sleeve 18 tight against the left-hand face of the plate 17 so that the sleeve 18 is rigidly secured to said plate 17. The end piece 4 is made with a hole 22 large 30 enough to admit the nut 21 with provision for more or less motion of said nut in a front and back direction. In other words, the hole is larger than the nut. The plate 17 is secured to the end piece 4 by means of two 35 screws 23 and 24, the one located in the vertical plane of the platen axis, in this instance directly below said axis, and the other preferably directly above said axis. One of said screws, for example, the screw 23, passes 40 through a round hole in the plate 17 and is screwed into the piece 4; but the other screw 24 passes through a slot 25 in the plate 17 which slot may be formed on a curve concentric with the screw 23. Another slot 26 45 is formed in the plate 17 and is elongated in a direction toward and away from the screw 23. A screw 27 with an elongated head eccentric to the shank or threaded part of the screw, passes through the slot 26 and is 50 screwed into the piece 4, the head of said screw 27 being of a diameter corresponding to the width of the slot 26.

In adjusting the machine the carriage may be moved to its extreme left-hand position 55 and a gage is set against the front face of the right-hand portion of the platen which at that time will be at the printing point. The carriage may then be moved to its extreme right-hand position and, the screws 60 23 and 24 being in place but not tightened, the screw 27 is turned one way or the other, the turning of said screw on account of the eccentricity of its head rocking the plate 17 one way or the other about the screw 23 as 65 a center. As said screw 23 is directly be-

neath the platen axle, turning the screw 27 will effect a fine adjustment of the left-hand end of the platen toward the front or back of the machine. By this means the left-hand end of the platen is adjusted exactly to the 70 gage which has previously been set to the right-hand end of said platen. When the left-hand end of the platen has been thus accurately adjusted it is secured in adjusted position by tightening the screws 23 and 24. 75 When this has been done both ends of the platen and therefore, of course, all parts of the platen will be set in exactly the same relation to the type bars when any of said bars is in contact with the anvil 16. 80

It will be perceived that the effect of the adjustment described is to set the front or printing face of the platen in exact parallelism with the carriage rails, or parallel with the direction of carriage travel. 85

While in practice I have found it necessary to employ only one set of the adjusting devices, it will be understood that two such sets may be used, one set at each end of the platen. Again, though I have applied my novel adjusting devices at the left-hand end of the platen, it will be understood that in some makes of machines it may be desirable or necessary to apply said adjusting devices at the right-hand end of the platen. 90

The character of the adjustment provided by my novel means, is diagrammatically illustrated in Fig. 5, where the broken line 28, drawn through the front face of the right-hand end of the platen parallel with the direction of carriage travel, represents the correct position of the said front face or writing line. If the left-hand end of the platen is found to be forward of or behind this line, it can be adjusted toward the back 100 or front until it is brought exactly to said line 28. In this figure of the drawing the left end of the platen is shown, in an exaggerated way, behind its proper position, and is to be adjusted toward the front. 105

In the drawing the invention is shown applied to a front strike machine, and in such case the adjustment is in a front and back direction; but in a machine in which the types strike at some different angle, as in a top strike machine, for example, the adjustment would be in a correspondingly different direction. In some of the claims I have referred to the adjustment as being "in printing point direction", meaning in the 115 direction of the radius of the platen at the printing point. 120

It will be noted that the platen axle has a long bearing in the sleeve 18, that said sleeve is rigidly mounted on the plate 17, 125 and that, when the screws 23 and 24 are tightened, said plate is held rigidly against the face of the end bracket 4 of the carriage. The bearing sleeve 18 is therefore firmly and accurately held in its adjusted position 130

and the platen frame is as rigid a structure as it would have been if the adjustment had not been provided.

Various changes can be made in the details of construction and arrangement without departing from my invention.

What I claim as new and desire to secure by Letters Patent, is:

1. In a typewriting machine, the combination with a platen and a platen frame having an end plate, of a bearing piece for the platen axle comprising a plate and a sleeve secured to said plate, and means for adjustably and rigidly securing the last mentioned plate against a face of said end plate of the platen frame.

2. In a typewriting machine, the combination with a platen, of a platen frame having an end plate with an opening there-through, a bearing piece for the platen axle comprising a plate and a sleeve secured to said plate, and means for adjustably and rigidly securing the last mentioned plate to a face of said end plate of the platen frame, said sleeve passing freely through said opening.

3. In a typewriting machine, the combination with a platen, of a platen frame having an end plate, a bearing piece for the platen axle comprising a plate and a sleeve secured to said plate, and screws adjustably and rigidly securing the last mentioned plate against a face of said end plate of the platen frame.

4. In a typewriting machine, the combination with a platen, of a platen frame having an end plate, a bearing piece for the platen axle comprising a plate and a sleeve secured to said plate, and screws adjustably and rigidly securing the last mentioned plate against a face of said end plate of the platen frame, said bearing plate before the screws are tightened, being adjustable about one of said screws as a pivot.

5. In a typewriting machine, the combination with a platen and a platen frame having an end piece, of a bearing piece for the platen axle comprising a plate, a bearing sleeve screwed through said plate and a nut screwed on said sleeve against said plate, and means for adjustably and rigidly securing the last mentioned plate against a face of said end plate of the platen frame.

6. In a typewriting machine, the combination of a platen, a platen frame, a plate carried by one end of said platen frame, means for effecting a fine adjustment of said plate in printing point direction and for then securing said plate rigidly to said end piece, a sleeve secured to said plate, and a platen axle journaled in said sleeve.

7. In a typewriting machine, the combination of a platen having an axle, a platen frame having an end piece, a plate mounted against the face of said end piece, means

for effecting a fine adjustment of said plate in printing point direction and for then securing said plate rigidly to said end piece, and a sleeve screwed into said plate and in which said axle is journaled.

8. In a typewriting machine, the combination of a platen having an axle, a platen frame having an end piece, a device supporting one end of the platen axle and secured to said end piece by means allowing an adjustment of said device about a pivotal center, and means for effecting such adjustment.

9. In a typewriting machine, the combination of a platen having an axle, a platen frame having an end piece, a device in which said platen axle is journaled, said device secured to said end piece by screws, one of which is capable of acting as a pivot about which said device can be adjusted, and means for effecting an adjustment of said device about said pivot before the screws are tightened.

10. In a front-strike typewriting machine having type bars and an anvil for said type bars, the combination with said type bars and anvil, of a platen, a platen frame, and means for effecting a fine adjustment of one end of said platen relative to the other end and independently of and relative to said platen frame in a front and back direction.

11. In a front-strike typewriting machine, the combination with front-strike type bars and an anvil for said type bars, of a platen having an axle, a platen frame having an end piece, an adjustable device secured directly to said end piece and comprising a sleeve in which said axle is journaled, and means for effecting a fine adjustment of said device in a front and back direction.

12. In a front-strike typewriting machine, the combination of a platen, a platen frame having an end piece, a device secured to said end piece and in which said platen is journaled, and means for securing said device to said end piece, said securing means including a screw in the vertical plane of the platen axis and about which said device can have a pivotal motion and another screw passing through a slot whereby said device can be adjusted about the first mentioned screw as a pivot before said securing screws are tightened.

13. In a typewriting machine, the combination of a platen having an axle, a platen frame having an end piece, a device in which said platen axle is journaled, said device secured to said end piece by screws, one of which is capable of acting as a pivot and the other of which is adapted to allow of a motion of said device about said pivot, and an eccentric for effecting a fine adjustment of said device about said pivot before said screws are tightened.

14. In a typewriting machine, the combination with type bars and an anvil for said

type bars, of a platen, a platen frame, and means on said platen frame for effecting a fine adjustment of one end of said platen relative to said platen frame independently of the other end of said platen, toward and from the point at which the type on an operated type bar is arrested by said anvil.

Signed at Ilion, in the county of Herkimer, and State of New York, this 4th day of October, A. D. 1916.

GEORGE A. SEIB.
